UNITED STATES PATENT OFFICE.

ELMER E. RAGON, OF GARY, INDIANA.

CONTAINER.

1,330,344.

Specification of Letters Patent. Patented Feb. 10, 1920.

Application filed May 3, 1919. Serial No. 294,469.

To all whom it may concern:

Be it known that I, ELMER E. RAGON, a citizen of the United States, and residing in Gary, Indiana, U. S. A., have invented a 5 new and useful Improvements in Containers.

My invention relates to water proof containers. The purpose of this invention is to furnish a depository for valuable and damageable articles carried as personal property 10 by persons who are entering water bodily, either intentionally or forcibly, such as bathers, or parties on a sinking vessel. A specific use is as a depository for jewelry and currency of a bather at a public bathing 15 place who does not wish to trust his effects to the checking room.

In the accompanying drawing, Figure 1 shows an elevation of the device in complete assembly, Fig. 2 shows a top view of the 20 same, Fig. 3 shows in elevation and cross section, the outer member, Fig. 4 similarly shows the inner member of the container, Fig. 5 shows in cross section an inner receptacle for holding a watch.

The invention consists in general, of two 25 metal capsules or cans, each with a screw cover, and preferably having a gasket of soft material such as cork within the cover, which serves to make a water tight seal, though 30 neither the gasket nor the water tight seal are essential parts of the invention, but are supplied for safety in case the device has been improperly assembled.

The outer can 1, which may be attached to 35 a belt by some means such as metal strap 2, has the screw cap cover 3, and is worn with the cover end down. The inner can 4, is inserted with the cover 5 at the top. Should any water enter the outer can, due to an 40 perfect seal by the cover, it would have to fill the entire space 6, between the cans be-

fore it could enter the inner can. This it will be unable to do, because the air within has no escape except by way of the cover, which path is effectively sealed by the water itself. 45

The inner can 4 may be made with an extending flange 7 from its base, which extends into the recess 8 in outer can 1, thus preventing the insertion of the inner can wrong 50 end first.

A third receptacle 10, with screw cover 11, may be mounted within cover 5, preferably by being attached to cover 5 in some manner such as by solder 14, or rivet 16. The wall 15 of receptacle 10 extends beyond the side 55 9 of cover 5 to enable the cover 11 to be readily grasped by the hand.

Within the receptacle 10 is a coil spring 18 attached to 10 as by rivet 16, and supporting a disk 12 by means of rivet 17. The tension of spring 13 is such that a watch will be firmly held between disk 12, and cover 11. The surfaces of disk 12 and cover 11 as well as the sides of wall 15 which come in contact with the watch may be lined with 65 felt to prevent any injury to the watch case.

Having thus described my invention, what I claim is,—

A container consisting of an outer and an inner capsule or can, each with a threaded 70 cover for its open end, one fitting within the other, the inner capsule or can having a third capsule or can, also with a cover, and attached within the cover of the inner capsule or can, the third capsule or can having 75 a spring attached within, supporting a disk or plate.

ELMER E. RAGON.
